RICHARD B. CARTER, OF BLAIR, NEBRASKA.

HOT-BLAST OIL-BURNER HEATER.

1,080,810.

Specification of Letters Patent.

Patented Dec. 9, 1913.

Application filed August 8, 1910. Serial No. 576,126.

To all whom it may concern:

Be it known that I, RICHARD B. CARTER, a citizen of the United States of America, residing at Blair, in the county of Washington and State of Nebraska, have invented 5 certain new and useful Improvements in Hot-Blast Oil-Burner Heaters, of which the following is a specification.

My invention relates to improvements in oil-burners applied to heaters for warming and ventilating buildings; and the objects of my improvement are, first, to combine in an oil-burner facilities for the perfect combustion of crude oils or distillates thereof 15 with means to properly ventilate the space or rooms warmed; second, to provide the burner with an automatic hot-blast supply of fresh air; third, to provide in the burner a retort to thoroughly volatilize or vaporize 20 the fuel before it is united with the hot-blast and ignited; fourth, to utilize the largest possible percent of all the thermal units by the perfect combustion of fuel, before the gases of combustion are carried away 25 through the ventilation exhaust duct; fifth, to eliminate the usual roaring sound common to the oil-gas or hydrocarbon burner and to produce a steady unflickering flame of perfect combustion; and, sixth, to so 30 arrange and construct the parts of the burner so as to facilitate the superheating of the hot-blast and prevent any cooling or condensation of the vapor-gas between the retort and the flame; these, with other minor 35 objects hereinafter more specifically set forth, I attain by mechanism illustrated in the accompanying drawings in which—

Figure 1 is a vertical sectional elevation on the dotted line *a* of Figs. 2, 4, 5 and 6; Fig. 2, a plan of the whole heater below the dotted line *b* of Figs. 1 and 3; Fig. 3, a vertical sectional elevation on the dotted lines *c* of Figs. 2, 4, 5 and 6; Fig. 4, a plan on the dotted line *d* of Figs. 1 and 3; Fig. 5, a plan on the dotted line *e* of Figs. 1 and 3; Fig. 6, a top view of the heater without the fuel tank; Fig. 7, a central vertical section at larger scale of the combustion-chamber and burner on the dotted lines *f* and *g* of Figs. 8 and 9 respectively, the tops of the remaining pipes 11 and 11 cut away to disclose their connection to the heating-drum; Fig. 8, a plan of the combustion and hot-blast chambers on the dotted line *h* of Fig. 7, a portion of the floor of the hot-blast chamber cut away to disclose the burner con-

nections beneath; Fig. 9, a vertical cross-section of the burner, combustion-chamber and lower part of the hot-blast chamber on the dotted lines *i* and *j* of Figs. 7 and 8 respectively; Fig. 10, a view of the under-side of the retort; and Fig. 11, a front or rear elevation of the retort.

In all of which views like reference numerals designate like parts of the structural contrivance and arrows indicating the direction of movement of the same gas or air currents in different views.

Primarily, the preferred form of my improved burner applied to a heater as disclosed by the drawings, comprises an axially-vertical cylindrical structure supported above the floor on legs 1 and having a central combustion-chamber and heat-dome 2 containing a hot-blast oil-burner in the base 75 thereof; an exterior concentric radiation chamber 3 also serving as a diving flue connected to the heat dome or top of the combustion-chamber; a heating or radiation-chamber 4 interposed concentrically between 80 the combustion and radiation chambers and open at bottom and top for the free passage of air taken up from near the floor; a horizontal base flue 5 connecting the base of the exterior radiation chamber with an exhaust-flue 6 to be connected to a chimney-flue of the building. And the liquid-fuel-burner, which is especially designed for consuming crude natural oils or distillates thereof, having a retort 7—8 interposed between a gas-jet 9 below and a downwardly discharged hot-air-blast from the hot-blast air-heating drum 10 above; which drum is supplied with cold or foul air from the floor of the room and partially heated while ascending 95 through the vertical pipes 11, 11 etc., all within said combustion chamber as shown. The heating of the vertical air-supply pipes, disposed within range of the flame, and the hot-blast drum above in the path of the hot 100 gases of combustion from the flame below, supplemented by the draft of the exhaust-flue, maintains a supply of hot air to the burner and promotes perfect and silent combustion.

A castiron base-plate 12 has the inner up-standing flange 13 to engage the lower end of the circular sheet-metal combustion-chamber casing 14. Also other upstanding flanges as shown, including the wide outer 110 vertical base-flange 15, to connect with the horizontal flange or top 16 and the inner

vertical flange 17 of the circular angle-casing to form the circular horizontal base-flue 5. The top 16 is also suitably flanged to connect the lower ends of the outer circular sheet-metal casing 18 and the like sheet-metal partition 19 between the radiation chamber 4 and the exterior chamber 3. This base-plate has the requisite apertures to receive the hot-blast supply pipes 11, 11, 10 etc., also a circular row 20 of openings to admit the air from below into the base of the radiation-chamber; it also has integral lugs on its bottom surface to engage the supporting legs 1. The top of the base-flue has the perforations 21 connecting it with the outer chamber above and a large rear opening to connect said base-flue with the exhaust-flue 6 which is a portion of the outer chamber divided off by the vertical 15 side partitions 22.

The top end of the radiation-chamber is terminated in a series of vertical ducts 23, 23 etc., with equal intervening spaces. To accomplish this the full size chamber is terminated at the castiron top or head 24 spaced a distance below the castiron domed top 25 of the entire heater. This head is shaped with top and bottom flanged openings agreeing in size and position with the 25 flanged openings 26, in the heater top and connected therewith by the interposed sheet-metal ducts 23, 23 etc., which form the discharge exits at the top of said radiation-chamber. These ducts are enlarged 30 convergently inward into the heat dome at the top of the combustion-chamber to preserve the area of cross-section of outlet from the chamber and to increase the hottest radiation surface thereof. This inward enlargement is extended downward at 28 below the head to avoid stricture of outlet and further increase the radiating surface. The spaces between said ducts and between the head and top above, serve as connecting ducts 35 from the combustion-chamber to the outer radiation of diving-flue chamber. The heater top has the elliptical opening flanged upward to form a tapered terminal nipple-rim 29 to connect the exhaust-flue to an ordinary sheet-metal smoke-pipe.

A pair of oscillating dampers 30 and 30 are disposed one at each side near the head of the exhaust-flue, as shown in Figs. 3 and 5. These dampers are rigidly mounted 45 on the horizontal rod 31 disposed through the flue and having one end extended out through the outer casing and bent to form the handle-eye 32 by which the rod is rocked and the damper-plates oscillated to cover or 50 open the direct-draft openings 33 and 33.

Opposite to the exhaust-flue and close down to the base-flue the jambs 34 are disposed to form a doorway through the outer and radiation chambers into the base of 55 the combustion-chamber, for access to the

burner. A closure 35, is hinged to close and lock against the outside, and has a transparent panel 36 through which the burner may be inspected to regulate the flame without opening the door to interfere with the 70 hot-blast supply.

While I have shown the fuel supply to be from a tank 37 supported on a shelf 38 in an elevated position to give the required head or pressure of flow to the burner, this 75 may be attained by air pressure in the top of the tank without elevating it. The vertical supply pipe 39 has the needle valve 40 placed as close as convenient to the burner to control and shut off the liquid fuel. Entrance is made to the combustion-chamber 80 vertically through the base-plate, so that the horizontal section 41 of the supply-pipe may be swung in a horizontal plane to bring the 85 heater to any desired position relative to the 85

The first element in the burner is the connected vertically disposed filter-pipe 45, having top and bottom ends filled with tight sifting foraminous diaphragms 46 and 46, 90 and the intervening space filled with a disintegrate granular substance, preferably clean small gravel 27, to form a filter through which the fuel supply must pass upward. Connected to this by an ordinary 95 pipe-fitting elbow is the horizontally disposed retort 7—8. A downward return bend 47, of like elbows and a short interposed vertical connecting pipe, is connected to the opposite end of the retort and supports the 100 connected horizontally disposed gas or vapor pipe 48 below the retort; and this gas-pipe has a jet-orifice 49 opening upward centrally beneath the retort.

The retort consists of the single length of 105 pipe 7 screw-threaded at its ends to connect with the fittings, and the heating-block and flame-spreader 8 of castiron disposed centrally around the pipe by casting on. This spreader is a horizontally disposed thick 110 disk having a wide bevel 50 around its top outer edge forming a frusto-conical top to deflect the descending hot-blast outwardly. The under surface 51 is concaved to form an inverted trough lying directly under and 115 parallel with the retort-pipe 7 to carry a larger portion of the gas and flame toward and around the filter and the oppositely disposed return-bend. The concaved underside and the adjacent nearly vertical edges 120 52 are smoothly polished, whereby any soot accumulation quickly cleaves off as the spreader becomes hot, even to redness, so that the retort receives the full effect of the 125 flame 53.

To supply a hot-blast of air to the burner to facilitate the silent and perfect combustion of the vaporized fuel, four vertical inlet pipes 11, 11 etc., are disposed at equal 130 distances apart around the burner and with-

in the combustion-chamber, as shown in Figs. 1, 2, 3, 4, 7, 8 and 9. Their lower ends are projected through the base-plate and down toward the floor to take up the coldest and foulest air of the room. Their upper ends terminate and open into the hot-blast heating-chamber or drum 10. The course of this blast of air is indicated by the arrows 56. This hot-blast air-heating chamber is a vertical cylindrical sheet-metal enclosure supported by the inlet pipes 11 and disposed centrally above the retort and concentrically in the combustion-chamber; and being of less diameter is spaced away from the walls of the combustion-chamber leaving a passage clear around for the ascending hot gases of combustion. A discharge duct 54 is disposed centrally and vertically through the lower head of the hot-blast chamber; this duct has the top end placed as close to the top head of the chamber as possible and not restrict the passageway to take out and down the heated air; and the lower or discharge end projects below the lower head terminating at the required height above the burner to discharge the hot-blast downward against the top of the heating-block and flame-spreader.

A drip-pan 55 is placed on the base-plate beneath the burner and supplied with a non-combustible fibrous mat to hold a supply of liquid fuel to burn when starting the burner.

In operation the dampers 30 are first opened, giving direct draft from the top of the combustion-chamber into the exhaust-flue, as indicated by the arrows 57 and 57, in Figs. 3 and 5. The controlling valve of the fuel supply is opened until a small amount of the oil has dripped down onto the mat in the pan and is ignited to first heat and start the burner. When the burner attains a working heat, the dampers and illuminated door are closed and kept closed and the size of the flame regulated by the controlling valve in the fuel-supply pipe.

While the retort proper 7-8 becomes heated to redness, all parts of the burner within the base of the combustion-chamber, including the air-intake pipes to the hot-blast, become very hot. The filter and opposite return-bend are made intensely hot by the flame directed around them by the particular direction of the concavity of the underside of the flame-spreader as described above. And the proximity and central position of the small short jet-orifice gas-pipe with reference to the flame and connected parts in the closed base of the combustion-chamber, where no cold currents can strike it, keep its temperature so close to that of the other portions of the fuel-duct in the burner, that there is no cooling or condensation of the highly heated and vaporized fuel between the retort and the flame. By cast-

ing or casting the heating-block and flame-spreader on the retort-pipe, forming a homogeneous or fused connection of the two metal parts, I attain a result, both in convenience of construction and efficiency of heating capacity, proven, by numerous experiments with other modes of close fitting them together, to be far superior.

In the heated filter a rapidly-expanding slowly-ascending current of fuel forestalls the possibility of any decomposable particles of the fuel, having any appreciable specific gravity, ever reaching the retort; this, supplemented by the intense superheating action of the retort serves to deliver against the spreader a highly rarefied superheated oil-vapor-gas. As this gas spreads out it is met by the downwardly discharged current of the hot-blast which is super-heated when it strikes the top of the intensely heated heating-block; at which line of meeting almost silent and perfect combustion takes place. The circular line of initial ignition of the gas is near the edge of the spreader, when the fuel supply is turned on to its greatest required volume. If the rate of supply of fuel is reduced the circular line of initial ignition reduces in diameter bringing more of the center of the flame in contact with the spreader and heating-block; whereby, the retort is retained nearly as hot by a small flame as when more fuel is being consumed; thus supplying a substantially uniform quality of vapor-gas for any required degree of heating.

The foul air taken up and discharged by the hot-blast and mixed with the gases of combustion rises to the top of the combustion-chamber 2; passes, as indicated by the arrows 58, 58, etc., outwardly over the head of and between the vertical terminal ducts above the head of the radiation-chamber 4; thence downward in the outer circular chamber 3 and through the openings at its base into the base-flue 5; thence backward to the base of and up the exhaust-flue 6.

I claim:

1. A hot-blast oil vapor-burner, comprising a combustion chamber having an exhaust opening, an oil supply pipe leading into said combustion chamber, and a filter in the oil supply pipe in said chamber; a retort consisting of a pipe disposed in the combustion chamber and having one end communicably connected to the filter and at its opposite end a return bend having a jet orifice opening toward a central portion of said pipe, a metal heating-block flame-spreader and hot-blast-deflector disposed centrally on said pipe by casting on and having a frusto-conical face, its opposite face disposed toward said jet orifice and troughed in alignment with said filter and said return bend; and a hot-blast device consisting of an air-heating drum disposed in

- the combustion chamber at the side of the retort opposite to said jet orifice, air pipes in the combustion chamber spaced around said retort and communicably connected 5 with the outer air and with said air-heating drum, and a discharge-pipe disposed part way through said drum and its discharge-end projected from the drum toward the frusto-conical deflecting face of the retort.
- 10 2. A hot-blast oil vapor-burner, comprising a combustion chamber having an exhaust outlet, an oil supply pipe leading upwardly in said chamber, a filter in said upwardly leading pipe, a horizontally disposed retort duct communicably connected at one end with the top of said filter its opposite end having a downwardly-disposed return bend and its underside troughed in alinement with said filter and bend, a vapor 15 gas-pipe communicably connected to said return bend and having a jet orifice opening upwardly toward the center of the troughed underside of the retort, an air-heating drum disposed in the combustion chamber and over the retort, vertical air 20 pipes in the combustion chamber and spaced around said retort their lower open ends disposed through the bottom of said chamber and their top ends communicably connected to said heating drum, and a vertical 25 hot-blast pipe disposed through the bottom of said heating drum its receiving end projected upwardly into the drum and its discharging end projected downwardly toward 30 the top of the retort.
3. A hot-blast oil vapor-burner, comprising a combustion chamber having an exhaust opening, a duct-retort disposed in said chamber and having a frusto-conical top 35 and a horizontally troughed bottom and the bottom and adjacent peripheral edge smoothly polished, a vertical oil supply pipe disposed in said chamber in alinement with the trough in the bottom of the retort and communicably connected with the duct 40 thereof, a pipe communicably connected to the opposite end of the retort duct by a downwardly disposed return bend in alinement with said trough and said pipe having 45 a jet orifice opening upwardly toward the center of said trough, an air-heating drum disposed in said chamber and above said retort, vertical air pipes in the chamber 50 spaced around said retort and communicably connected with the outer air and to said heating drum, and a hot-blast pipe leading downwardly from said heating drum to discharge on the top of said retort. 55
4. A hot-blast oil vapor-burner comprising a combustion chamber having an exhaust outlet, a hot-blast oil vapor retort having a fuel supply connection and a jet disposed in said chamber, an air-heating drum in said chamber, air pipes in said chamber spaced around said burner and communicably connected with the outer air and with said drum, and a hot-blast pipe having a receiving end disposed part way through said air-heating drum and its opposite discharging end projected from said drum toward 60 said burner. 65
5. An oil vapor burner, comprising a horizontally-disposed retort-pipe, a vertical oil supply pipe connected at its top end to one end of the retort pipe, a filter in the top end of the vertical oil supply pipe, a downwardly-disposed return bend duct connected to the opposite end of the retort pipe, a circular heating-block and flame-spreader of metal cast on the center of said retort pipe 70 and its bottom face shaped to form an inverted trough disposed in alinement with said oil supply pipe and said return bend, said bottom face and the adjacent peripheral circular edge of the heating-block and 75 flame-spreader smoothly polished, and a gas-pipe connected to said return bend, disposed beneath the retort and having a jet 80 orifice opening upwardly toward the center of the trough in the bottom face of the 85 heating-block and flame-spreader. 90
6. A retort for hot-blast oil vapor burners, comprising a straight metal pipe with open coupling ends, a metal heating-block, flame-spreader and hot-blast-deflector, cast around 95 an intermediate portion of the pipe and having a face shaped to form a trough disposed parallelly with the pipe and an opposite frusto-conical face.

In testimony whereof I affix my signature 100
in presence of two witnesses.
